UNITED STATES PATENT OFFICE.

JOHN L. MOHUN, OF BROOKLYN, NEW YORK.

CAR-ROOF.

1,077,632.

Specification of Letters Patent.

Patented Nov. 4, 1913.

Application filed December 21, 1911. Serial No. 667,070.

To all whom it may concern:

Be it known that I, JOHN L. MOHUN, a citizen of the United States, residing at Brooklyn, in the county of Kings and State of New York, have invented new and useful Improvements in Car-Roofs, of which the following is a specification.

This invention relates to car roof construction, and more particularly to what is known as inside car roof structure in which the roofing boards are located outside or above the metal roof sheets.

One of the objects of my present invention is to provide an improved flexible sheet metal roof construction which may be supported directly upon the purlins and ridge pole and drain over the side plates of the car.

Another object is to provide improved means for supporting the outside roofing boards above the metal roof at the eaves and at the ridge of the car whereby the roof may be readily assembled and the boards secured without nailing.

Another object is to provide improved means for ventilation beneath the metal roof at the eaves of the car.

In the accompanying drawings: Figure 1 is a transverse section of a portion of a car roof embodying one form of my improvement; Fig. 2, a longitudinal section of the same, on a larger scale, taken at the center of the car ridge; Fig. 3, a longitudinal section through a portion of the roof, taken on the line 3-3 of Fig. 1; Fig. 3a, a detail view of the bar for supporting the lower ends of the roofing boards; Fig. 4, a side elevation of the carline hood and bracket; Fig. 5, a horizontal section of the same, taken on the line 5-5 of Fig. 4, and showing the connection with the lateral drain trough; Fig. 5a, a perspective view of the lower end of the lateral drain trough; Fig. 6, a plan showing the connections at the running board saddle, the running boards being removed; Fig. 7, a longitudinal section of the ridge hood, and a portion of the roof at the end of the car; Fig. 8, an end elevation of the same, the running board bracket being omitted; and, Figs. 9 and 10, a transverse section and a side elevation, respectively, showing means for ventilating beneath the metal roof sheets at the eaves of the car.

The supporting frame work of the car

roof may be constructed in the usual way by means of carlines, 20, supported on the side plates, 21, and carrying purlins, 24, and a ridge pole, 25, the carlines, purlins and ridge pole, being of any suitable or preferred construction.

According to one feature of my present improvement, the metal roof sheets, 23, which extend from the ridge to the eaves of the car, are supported directly upon the roof frame-work, and the upper and side edges of said sheets are turned up and over and down so as to drain into drain troughs, 32, which are located on the frame-work between adjacent edges of the roof sheets and discharge over the side plate at the eaves of the car. The lower end of each lateral drain trough is covered and held in place by a carline hood, 30, bolted to the side plate and having lugs, 32, for engaging the ends of the sides of the drain troughs, 32, as shown in Figs. 4 and 5, the bottom of the trough being bent down and flared out at 32a beneath the hood and over the side plate and facia board.

The running board saddle may be formed in two parts, the lower casting having projections, 27 and 28, connecting respectively with the lateral drain troughs, 32, and the ridge trough, 26, mounted on the ridge pole, 25, and an upwardly extending web, 29, to which the upper casting, 40, is bolted and supports the running boards, 41. The casting, 40, is also provided with flanges for covering the ends of the lateral caps, 22, and the ridge caps, 33, as more fully set forth in my co-pending application, filed December 21, 1911, Serial No. 667,069.

In the present instance, the metal roof construction is located directly upon the frame work of the roof and the water which collects in the ridge trough and lateral drain troughs from the roof sheets drains through the discharge from said troughs over the side of the car.

For the purpose of supporting the roofing boards, 30, above the metal roof sheets and caps, I provide a bracket, 61, at the eaves supporting a U-shaped metal bar 44, which holds the lower ends of the roofing boards, 30. The bracket is preferably formed as an integral part of the carline hood, 30, as shown, and the U bar, 44, may be provided with a series of drain holes for the escape of water therefrom. For supporting the

upper ends of the boards, an inverted T bar, 43, may be supported on lugs formed on the running board saddle, 40, the ends of the boards being covered and held in place by 5 a bar or key block, 42, which is also carried upon and between lugs cast upon the side of the saddle and beneath the running boards.

The ridge hood, 66, has a vertical arm 64, which may be fastened to the running board, 41, for giving the hood greater stability in assisting to support the outside roofing boards, for which purpose it may be provided with lugs, 65, for holding one end of the T bar, and lugs, 67, carrying the end of 15 the key block, 42. The hood, 66, may also be formed with interior lugs, 63, for holding the ends of the sides of the ridge trough, 26, the bottom of which is bent down and flared out at 26^a, over the end facia board, 20 as shown in Figs. 7 and 8. The hood, 66, also covers the end of the ridge cap, 33, and is bolted to the end plate of the car.

In order to improve the ventilation of the interior of the car, notches or passages, 70, 25 in the side plates, 21, and corresponding passages, 71, in the top of the facia board, 58, may be provided beneath the roofing sheets, 23, which are bent down over the side plate and top of the facia board and are fastened 30 to the side plate by means of bolts, as shown in Figs. 9 and 10 of the drawings. By this means the fresh air may pass freely through said notches or passages into the interior of the car beneath the metal roof, thereby 35 ventilating and cooling the same and at the same time excluding any rain or moisture.

While my improvement is shown as applied in connection with outside roofing boards, it is to be understood that the features relating to the flexible metallic roof 40 construction supported directly upon the roof frame-work may be used independently, and the outside roofing boards with their supports be dispensed with, if desired, as 45 will be evident.

Having now described my invention, what I claim as new, and desire to secure by Letters Patent is:—

1. In a car roof, the combination with an 50 inside metal roof, of outside roofing boards, a metal bar supporting the lower ends of said boards and having an integral portion extending over the top edge of said boards holding said boards in place, and means 55 supporting said bar above the metal roof sheets.

2. In a car roof, the combination with an 60 inside metal roof, of outside roofing boards, a metal U bar inclosing the lower ends of said boards, and means supporting said U bar above the metal roof.

3. In a car roof, the combination with an 65 inside metal roof, of outside roofing boards, a metal U bar inclosing the lower ends of

said boards, and a metal bracket supporting 65 said bar above the metal roof.

4. In a car roof, the combination with inside metal roof sheets, of outside roofing boards, running board saddles extending 70 above said roofing boards and a bar supported on the saddles above the metal roof and holding the upper ends of the roofing boards.

5. In a car roof, the combination with inside metal roof sheets and running boards 75 saddles, of outside roofing boards, a bar supported on the saddles for holding the upper ends of the roofing boards, and a longitudinal bar covering the ends of said boards and holding the same in place. 80

6. In a car roof, the combination with inside metal roof sheets, and lateral drain troughs located at the side edges of said sheets, of outside roofing boards, a bar for supporting the lower ends of said boards, 85 and hoods for protecting the ends of said troughs and having means for supporting said bar.

7. In a car roof, the combination with metal roof sheets and lateral drain troughs 90 located at the adjacent side edges thereof, and extending to the side plates, of caps covering said troughs, and hoods covering the ends of said drain troughs and caps and having lugs for engaging the sides of said 95 troughs.

8. In a car roof, the combination with metal roof sheets and lateral drain troughs located at the side edges thereof, of caps 100 covering said troughs, and hoods covering the ends of said drain troughs and caps and having lugs for engaging the sides of said troughs, the bottom of said troughs being extended beneath the hoods.

9. In a car roof, the combination with 105 metal roof sheets and a ridge drain trough at the upper edges of said roof sheets, of a ridge covering the end of said trough and having lugs for engaging the sides thereof, 110 the bottom of the trough being extended beneath the hood.

10. In a car roof, the combination with metal roof sheets and a ridge drain trough at the upper edge of said sheets, of a ridge cap covering said trough, and a ridge hood 115 covering the end of said trough and cap and having lugs for engaging the sides of the trough.

11. In a car roof, the combination with an inside metal roof, outside roofing boards, 120 and a running board, of a ridge hood fastened to the end plate and to the running board, and a bar supported on said hood for carrying the outside roofing boards.

12. In a car roof, the combination with an 125 inside metal roof, outside roofing boards, and a running board, of a bar for supporting the upper ends of the roofing boards at the

ridge, and a ridge hood fastened to the running board and having a flange for supporting the ridge bar.

13. In a car roof, the combination with 5 the side plate of the car, and a facia board secured to the side plate below the top thereof, of metal roof sheets resting on the top of the side plate, and having their ends bent down over the same and resting on the top 10 of said facia, the side plate and facia being

provided with a plurality of notches or openings beneath the roof sheets for ventilation.

In testimony whereof I have hereunto set my hand.

JOHN L. MOHUN.
